UNITED STATES PATENT OFFICE.

DANIEL A. MORRISON, OF WINTER HARBOR, MAINE.

WHIFFLETREE.

SPECIFICATION forming part of Letters Patent No. 735,558, dated August 4, 1903.

Application filed November 14, 1902. Serial No. 131,380. (No model.)

To all whom it may concern:

Be it known that I, DANIEL A. MORRISON, residing at Winter Harbor, in the county of Hancock and State of Maine, have invented 5 certain new and useful Improvements in Whiffletrees; and I do hereby declare the following to be a full, clear, and exact description of the invention, such as will enable others skilled in the art to which it appertains to make and use the same.

This invention relates to whiffletrees; and it consists in the novel construction and combination of the parts hereinafter fully described and claimed.

15 In the drawings, Figure 1 is a plan view of the whiffletree. Fig. 2 is a cross-section taken on the line $x-x$ in Fig. 1.

A is a clevis provided with a ring b at its looped rear end a' , and B is a hook on the 20 ring b for attaching the clevis to the object to be drawn along. The clevis has converging portions b' and a jaw c at its front end.

C is a sheave which is journaled on a pin d in the jaw c , so that its groove forms an 25 unbroken continuation of the converging portions b' .

D is the whiffletree, which is pivoted on a pin e in the middle part of the clevis.

E is a chain or other flexible connection 30 which passes around the sheave C and has

its ends connected to the inner or adjacent draft-tugs of the animals.

F represents chains or other flexible connections which are connected to the ends of the whiffletree and to the outer tugs of the 35 draft-animals.

The peculiar formation of the clevis and sheave prevents the chain E from ever catching or becoming jammed in the clevis.

What I claim is—

The combination, with a clevis having at its front end converging portions and a forked jaw which is narrower than the main portion of the clevis, of a draft attachment connected to the rear end of the clevis, a sheave 45 journaled in the said forked jaw with its groove arranged to form a continuation of the said converging portions, a whiffletree pivoted in the middle part of the clevis and free to rock without disturbing the alinement 50 of the draft attachment and sheave, a flexible connection passing over the said sheave, and connections attached to the ends of the whiffletree, substantially as set forth.

In testimony whereof I affix my signature 55 in presence of two witnesses.

DANIEL A. MORRISON.
